UNITED STATES PATENT OFFICE.

WILLIAM DONLEY, OF CONESVILLE, OHIO.

FLOORING-CLAMP.

SPECIFICATION forming part of Letters Patent No. 232,470, dated September 21, 1880.

Application filed June 2, 1880. (No model.)

To all whom it may concern:

Be it known that I, WILLIAM DONLEY, of Conesville, in the county of Coshocton and State of Ohio, have invented certain new and 5 useful Improvements in Carpenter-Tools—viz., Flooring-Clamps; and I do hereby declare that the following is a full, clear, and exact description thereof, reference being had to the accompanying drawing, and to the letters of 10 reference marked thereon, which form part of this specification.

My invention relates to that class of tools used by carpenters for clamping and forcing into place the floor or weather-boarding of a 15 building; and it consists in two pivoted levers whose long arms are used as handles and whose short arms are curved toward each other in a regular curve, ending in a point adapted to enter the wood, and provided or 20 formed just behind the point with an anvil-shoulder for forcing it into hard woods, substantially as will be hereinafter more fully set forth and claimed.

In order to enable others skilled in the art 25 to which my invention appertains to make and use the same, I will now proceed to describe its construction and operation, referring to the annexed drawing, in which the figure represents a side view of my invention.

30 A represents the short arms of two levers, which are pivoted together at *a* and are extended beyond the pivot to form long handles B B. The short arms of these levers are bent in a regular curve in opposite directions, widening out in their center and nearly meeting at their extremities, where they end in short spear-like points *b b*, extending toward each other. Just behind these points the arms are formed with an anvil-shoulder, *c c*, by striking 35 on which they are forced into woods too hard to enter by the compression of the handles.

When in use the joist or studding is clamped with the tongs, the points *b* being forced into the wood to secure a firm hold, and the side 40 of the instrument pressed against the boards

forces them into place, where they are secured. When the wood is very hard or full of knots a few blows of a hammer on the anvil-shoulder provided for that purpose will often be necessary in order to secure a firm grasp.

I am well aware that flooring-tongs have been made very much resembling mine, as, for instance, that of E. J. Houston, patented February 18, 1873; but in this device the clamping-arms are almost straight and have 50 the points upon the inner sides of their extremities. In this construction the arms are very liable to become bent, cannot grasp a wide joist as securely, and when struck upon the back to force the points into the wood are 55 liable to soon become bent, battered, and misshapen. In my instrument the regular curve given to the arms enables me to grasp with ease and firmness a much wider joist or beam, is much stronger and less liable to bend, and 60 is provided especially with an anvil-shoulder in rear of the point to receive the blows of the hammer. The points also are not formed upon the side of the arm, but are formed by a continuation of the curve of the clamping-arm, and 65 are much stronger and better adapted to firmly grasp the beam.

Having thus fully described my invention, what I claim as new, and desire to secure by Letters Patent, is—

The within-described flooring-tool, consisting of two pivoted levers, A A, the shorter arms of which are curved from their pivot-point to their outer ends, as shown, and there terminating with an edge or point, *b b*, back 70 of which are formed the anvil-shoulders *c c*, all constructed and arranged substantially as herein set forth.

In testimony that I claim the foregoing as my own invention I affix my signature in presence of two witnesses.

WILLIAM DONLEY.
